BOOSTER PILOT VALVE RELAYS OF THE PNEUMATIC TYPE

Ray S. Williams, Orrville, Ohio, assignor to Hagan Corporation, Pittsburgh, Pa., a corporation of Pennsylvania

Application July 27, 1954, Serial No. 446,089

4 Claims. (Cl. 137—84)

This invention relates to pneumatic relays of the type which includes a signal-responsive pilot valve assembly and a booster pilot valve assembly that is actuated by the pressure output of the signal-responsive pilot valve assembly, the relay being so constructed that for every signal input pressure there is a corresponding pressure output by the booster pilot valve, means being provided for balancing the signal input by the booster pressure output.

An object of this invention is to provide a pneumatic relay of the type having a diaphragm pilot valve assembly which receives a variable input pressure, and develops by its pilot valve a corresponding pneumatic pressure output, and which includes a booster pilot valve assembly that transmits quickly an output signal in response to the pilot valve signal, and means for balancing the input signal with the booster valve output pressure.

A still further object of the invention is to provide a relay which is compact and of relatively simple construction and which is an improvement upon the relay disclosed in my copending application Serial No. 371,275, filed July 30, 1953.

Other objects of the invention will be apparent to those of ordinary skill in the art to which the invention pertains from the following description and drawings.

In the drawings:

Figure 1 is a view in longitudinal section of a relay having an input signal pilot valve assembly and a booster pilot valve assembly, arranged and constructed in accordance with an embodiment of the invention; and

Fig. 2 is an enlarged view in section of a portion of the signal input responsive pilot valve assembly.

In Fig. 1 of the drawings a relay 1, embodying what now appears to be a preferred form of the invention, is shown that comprises a housing composed of a flanged tubular member 2, a plurality of relatively thick disc-like members 3, 4, 5 and 6, a spacer 6' and an end cap member 7.

The relay includes a pilot valve 8 which is operatively connected to a pressure input signal responsive diaphragm 9 and a booster pilot valve 10 that is operatively connected to a pair of diaphragms 11 and 12. As shown the marginal edge of diaphragm 9 is disposed between disc members 3 and 4 while the marginal edge of diaphragm 11 is disposed between member 5 and the spacer disc 6', and diaphragm 12 is disposed between spacer 6' and disc member 7.

The abutting faces of members 4 and 5 and members 5 and 6' and 6' and 7 are sealed by gasket members 14, 14', 15, and 15'.

Member 4 is provided with an inlet port 17 that leads through a passage 18 into the space within member 4 and to the right of diaphragm 9. Member 5 is provided with a port 19 to which a supply of air at constant pressure may be connected. Port 19 is provided with a passage 20 that leads to the inlet of valve 8. Members 5, 6, 6' and 7 are provided with connecting ports forming a passageway 21 leading to the inside of member 7 to

2

form a supply for valve 10. Members 6, 6' and 5 are also provided with connecting ports forming a passage 22 leading to an output port 23 in member 5. Members 3, 4 and 5 are also provided with communicating ports 5 that form a passage 24 that connects the outlet port 23 with a chamber 25 on the left side of diaphragm 9.

Valve 8 controls the pressure supplied to the left side of diaphragm 11. That pressure operates valve 10 to lift it off its seat which is formed in a disc or plate 26. When 10 lifted off its seat, pressure is supplied from port 19 through passageway 21 through the valve seat of valve 10 to the passageway 22 to the outlet port 23. The outlet pressure at port 23 is communicated through the passageway 24 to the space 25 so that that pressure acts on diaphragm 9 to oppose the pressure supplied through port 17 to the opposite side of diaphragm 9.

If the signal pressure to port 17 decreases, valve 8 is moved in a direction to exhaust pressure from the diaphragm 11 through an exhaust passageway 28 formed in member 4. When pressure is relieved from diaphragm 11 diaphragms 11 and 12 move to the left whereby an exhaust port member 30 is moved away from the inner end of valve 10 thereby allowing pressure in passage 22 to exhaust to atmosphere through an exhaust port 31. Pressure is also exhausted from the space 25 so that the pressure on diaphragm 9 is relieved to a value where it balances the signal pressure acting on the opposite side of diaphragm 9.

The booster valve output pressure at port 23 is delivered 30 to some suitable device to be actuated in accordance with the magnitude of the signal pressure delivered to port 17.

The pilot valve assembly that responds to the input signal at port 17 comprises the valve 8 and a valve body 33 that is seated in a bore 34 in member 5. The valve body 33 is provided adjacent its opposite ends with grooves for accommodating sealing rings 35 and 36. Between the sealing rings 35 and 36 the valve body is ported as at 37 through which port the outlet pressure of valve 8 is transmitted through a passage 39 to the diaphragm 11. The valve body 33 has a bore extending through it in one end of which is a cup-shaped member 40 having in its closed end an inlet port 41 that is controlled by the tapered end 42 of valve 8. The opposite end of the valve body is provided with a threaded cup-shaped member 43 that is screwed into the valve body as shown. The closed end of member 43 is provided with an exhaust valve port 44 that is controlled by the pointed end 45 of valve 8. Member 43 may be adjusted into or out of the valve body 33 to provide the proper spacing between the inlet port 41 and the exhaust port 44 with respect to the pointed or cone-shaped ends 42 and 45. The valve 8 is provided with a stem 46 that is connected to a link 47 that transmits motion from diaphragm 9 to the valve 8. Link 47 and member 43 are encased in a flexible member such as a bellows 48. One end of bellows 48 is joined as by brazing, welding or soldering, to a flanged apertured disc 49 that is clamped between the central portion of member 5 and a flange 50 of member 4, a gasket in the form of an O-ring 51 being provided to form a fluid tight joint. The opposite end of bellows 48 is connected to a washer 53 as by soldering, brazing or welding. Diaphragm 9 is connected to a flanged sleeve 54 by means of a bolt 55 having a cupped head 56 which receives one end of member 47. Member 54 is internally threaded to accommodate a portion of member 55 that passes through the washer 53. By screwing member 55 into member 54 a pressure-tight joint is formed at the point where member 55 passes through the diaphragm 9.

A compression spring 56 disposed between a bonnet 57 and the flange of member 54, urges the diaphragm 9 to the right. Member 57 as shown is threaded into the neck

of member 2. A tension spring 58 is connected at one end by a threaded plug 59 to member 54 and by a threaded plug 60 to a ferrule 61 that is secured to a spindle 62. The spindle 62 passes through the head of member 57 and is threaded to accommodate a nut 63 secured to a sleeve 64. 5 provided with a hand wheel 65.

As shown the member 57 is slotted as at 66 to accommodate a screw 67 by which the ferrule is secured to the spindle 62. Thus when the hand wheel 65 is turned the ferrule and spindle 62 move in or out of the member 57 thereby increasing or decreasing the tension in spring 58. 10 By adjusting the tension on spring 58 the net force exerted by spring 56 on the flanged member 54 can be adjusted. By adjusting these spring forces, the initial loading on diaphragm 9 can be preset to any desired value and thereby predetermine the set point of the relay.

A bellows 70 is disposed about the shank of member 54. One end of the bellows is joined to the inner end of the shank 54, that is to the end adjacent diaphragm 9, and the opposite end is secured as by brazing, welding or soldering, to an apertured disc 71. The margin of the disc 71 is clamped between member 2 and a flange 72 of member 3, a gasket in the form of an O-ring 74 being provided to form a pressure tight joint. The bellows 70 and diaphragm 9 thus form the pressure chamber 25 to which the output pressure from valve 10 is supplied. For the same reason the bellows 48 and diaphragm 9 form the pressure chamber for receiving the input signal from port 17.

Valve 10 is urged towards its seat by means of a relatively light compression spring 74. Valve member 30 is urged off its seat or out of engagement with the inner end of valve member 10 by means of a compression spring 77.

As shown in the drawing valve member 30 is provided with a flanged head 78 that bears on one side of diaphragm 12. The stem of valve 30 is threaded to accommodate a flanged member 79 which is screwed down tightly on the diaphragm 12 to seal the opening through which the member 30 passes.

If it be assumed that the relative spring tensions of springs 56 and 58 are such that both ports of valve 8 are closed when the signal pressure to port 17 is zero and if it be assumed that under these conditions of spring adjustment, the signal pressure to port 17 is increasing from say zero gauge, then diaphragm 9 will be deflected to the left whereby valve 8 is moved towards its exhaust port seat thereby opening the inlet port 41. Pressure will then flow from port 18 through the cup member 40 into the body 33 and thence upwardly through port 37 and passageway 39 to the space to the left of diaphragm 11. That pressure urges diaphragm 11 to the right whereby valve 10 is opened and supply pressure flows from port 19 into the bonnet of member 7 thence through valve 10 and passage 22 to the outlet port 23. Pressure at the outlet port is also communicated through passage 24 to the left side of diaphragm 9. It will be observed from the drawing that the areas of diaphragm 9 exposed to pressure from port 17 and from the port 23 are equal. Therefore, as soon as the pressure at the outlet port 23 is equal to the signal pressure, valve 8 will come to a position where the pressure at the outlet port 23 balances the signal input pressure at port 17. As the signal input pressure increases the output pressure at port 23 will increase but for every value of pressure established by the input signal pressure at port 17 there will be a corresponding and equal pressure at the outlet port 23.

If the signal input pressure decreases then the spring tension acting on diaphragm 9 will move it towards the right thereby either throttling or closing the inlet port 41 and opening the exhaust port 44. The pressure acting on diaphragm 11 will therefore decrease, being exhausted through the exhaust port 44 and the exhaust passageway 28 to the atmosphere. As the pressure on diaphragm 11 is decreased, the tension of spring 77 will move valve member 30 to the left and unseat it from the stem of valve 10 whereby the pressure at the outlet port 23 will

exhaust through the member 30 to the atmosphere via the exhaust passage 31. When the pressure at port 23 has been decreased to a point where the pressure acting on diaphragm 11 is balanced, the exhaust port member 30 is again closed.

Thus for every value of input pressure through the signal input port 17 there will be a corresponding pressure delivered at the outlet port 23 and that pressure will balance the input signal pressure.

As can be seen from the drawings the pilot valve 8 is relatively small and handles relatively small quantities of air. That pressure, however, is sufficient to actuate the larger booster pilot valve which can handle larger quantities of air and thereby cause the apparatus responding to the pressure at the outlet port 23 to respond quickly to any change in the signal input pressure at the port 17.

By adjusting the relative tension of spring 58 with respect to the opposing tension of spring 56 the set-point of the relay can be changed. If the tension in spring 58 is increased, to thereby offset the compression of spring 56, valve 8 will establish a pressure at the outlet port 23, that is a function of the spring force acting on the diaphragm. In other words, with a zero signal pressure at port 17 the spring tension 58 may be so adjusted that the pressure at the outlet port 23 will be say ten pounds gauge. If now the signal pressure is increased from zero gauge to some higher value the pressure at the outlet port 23 will be ten pounds plus the pressure that is established by the signal input pressure.

If the tension in spring 58 is relieved so as to cause spring 56 to have greater force on the diaphragm, then the valve 8 will not be actuated until the signal pressure at port 17 is sufficient to overcome the net spring force acting on the diaphragm.

By means of the hand wheel 65 the relative tensions of springs 56 and 58 may also be adjusted manually to cause the relay to transmit pressure through the outlet port 23. In such a case the value of the output pressure will be proportional to the spring force acting on diaphragm 9 because the pressure acting on diaphragm 9 will come to equilibrium at that value which will produce a pressure force equal and opposite to the spring force.

Having thus described the invention it will be apparent to those skilled in this art that various modifications and changes may be made in the illustrated embodiment without departing from either the spirit or the scope of the invention.

Therefore what is claimed as new and desired to be secured by Letters Patent is:

1. A pneumatic booster pilot relay comprising a sectional housing, one section of said housing having therein a pilot valve body provided with inlet and exhaust ports and an outlet port, and a valve member for controlling the exhaust and inlet ports, said valve member being movable from one port to the other to restrict the inlet port while uncovering the outlet port and vice versa, said one section having a port for the supply of fluid pressure to said valve, a second section of said housing being provided with a diaphragm forming within the same opposed chambers, link means connecting said diaphragm to said pilot valve member for actuating the same to control said inlet and exhaust ports, spring means and a coupling therefor connected to said link, flexible seals in said chambers and disposed about said spring means coupling and said link to form with said diaphragm opposed pressure tight pressure receiving chambers, one of said chambers being ported to receive a pressure input signal while the other chamber is ported to receive a balancing booster output pressure, a third section of said relay housing comprising a chambered member having within the chamber a booster pilot valve comprising a movable valve member having a stationary outlet seat, the interior of the housing being connected to the supply port of the first mentioned section, a diaphragm assembly in said booster section which is port connected to the

outlet port of said pilot valve, said diaphragm assembly having at its central portion an exhaust valve member disposed to engage and unseat the movable booster pilot valve member from its seat in response to pressure being supplied to said diaphragm assembly by said pilot valve, said booster pilot valve discharging pressure against the diaphragm assembly of said third section to cause said diaphragm to close the booster pilot valve when the forces of said booster and pilot valve outlet pressures on said diaphragm assembly are balanced, means connecting said booster outlet pressure to an outlet port and to the balancing chamber of the first mentioned section, the exhaust valve member being actuated to exhaust position when the outlet pressure exceeds the pilot valve output pressure, whereby for every input signal pressure acting on the pilot valve actuating diaphragm the booster valve transmits a pressure whose value is sufficient to balance the force exerted by the input signal on the pilot valve actuating diaphragm.

2. A relay as in claim 1 in which the booster pilot valve diaphragm assembly comprises spaced diaphragms the central portions of which are secured to the booster exhaust valve member, said exhaust valve member being hollow and open at its opposite ends, one end being connected to the space between said diaphragms and the other end being disposed to engage the movable booster pilot valve to open the same and when so engaged said exhaust valve is closed, the said third section having an exhaust port connected to the space between said diaphragms, and spring means urging the exhaust valve member away from the movable booster pilot valve member toward exhaust position.

3. A relay as in claim 1 in which the spring means connected to the diaphragm of the first section comprises a relatively strong compression spring adapted to exert a force in the same direction as the balancing pressure acts on the pilot valve actuating diaphragm and a tension spring disposed to exert a force in opposition to said compression spring, and means connected to said tension spring for adjusting the force exerted by said tension spring relative to the force exerted by said compression spring whereby the set point of the relay may be adjusted and whereby the relay may be operated manually to effect operation of the pilot and booster pilot valves.
4. A relay as in claim 1 in which the pilot valve of the first section comprises a cylindrical valve body having a cylindrical bore therethrough and inverted cup-shaped members in the ends of said bore, said cup-shaped members being provided with inlet and exhaust ports respectively, a movable valve member having conical surfaces at its opposite ends disposed to coact with said inlet and exhaust ports to control the relative restrictions thereof and thereby control the pressure transmitted through the outlet of said valve body, the cup-shaped member provided with the exhaust port being ported, said first section having an exhaust passage leading to the atmosphere and connected to said exhaust port.
